UNITED STATES PATENT OFFICE

JOSEPH H. DICKER, OF JERSEY CITY, NEW JERSEY

DESIGN FOR A WAFER CONTAINER FOR ICE CREAM AND THE LIKE

Application filed August 29, 1932. Serial No. 44,714. Term of patent 3½ years.

To all whom it may concern:

Be it known that I, JOSEPH H. DICKER, a citizen of the United States, residing at Jersey City, N. J., in the county of Hudson and State of New Jersey, have invented a new, original, and ornamental Design for Wafer Container for Ice Cream and the like, of which the following is a specification, reference being had to the accompanying drawing, forming part thereof,

Fig. 1 is a side view of a wafer container for ice cream and the like, showing my new design.

Fig. 2 is a front view thereof.

Fig. 3 is a top plan view thereof.

Fig. 4 is a bottom view thereof.

I claim:

The ornamental design for a wafer container for ice cream and the like, as shown.

JOSEPH H. DICKER,
